C. W. OTT.
VEGETABLE SLICER.
APPLICATION FILED MAY 22, 1914.

1,137,017.

Patented Apr. 27, 1915.

UNITED STATES PATENT OFFICE.

CHARLES W. OTT, OF PITTSBURG, KANSAS.

VEGETABLE-SLICER.

1,137,017.

Specification of Letters Patent.

Patented Apr. 27, 1915.

Application filed May 22, 1914. Serial No. 840,244.

To all whom it may concern:

Be it known that I, CHARLES W. OTT, a citizen of the United States, residing at Pittsburg, in the county of Crawford and State of Kansas, have invented certain new and useful Improvements in Vegetable-Slicers, of which the following is a specification.

This invention relates to vegetable cutters and has for its object to produce a device susceptible of cutting a vegetable into slices and of adjustment to cut slices of different thicknesses, and adapted for use with splitting attachments for coöperating with the slicing means in cutting a vegetable, such as a potato, in strips of different thicknesses, such as "French fried" and "shoestring" potatoes, or a cabbage into slaw, efficiently and rapidly.

20 To these ends the invention consists in certain novel and peculiar features of construction and organization as hereinafter described and claimed; and in order that it may be fully understood, reference is to be had to the accompanying drawing, in which:

Figure 1, is a top plan view of a vegetable cutter embodying my invention, the cutter being arranged for producing "French fried" potatoes. Fig. 2, is a vertical section on the line II—II of Fig. 1. Fig. 3, is a vertical section on the dotted line III of Fig. 2. Fig. 4, is a sectional perspective view showing the cutter arranged for producing "shoestring" potatoes. Fig. 5 is a detailed perspective view of a gage forming a feature of the invention. Fig. 6, is a fragmentary perspective view of a fingered plate forming a part of the invention.

40 In the said drawing, 1 is a U-shaped bracket provided with a clamping screw 2 and adapted to fit over the edge of a table 3 and be clamped thereon by said screw 2. The upper arm of the bracket is provided with a step-shaped standard comprising vertical portion 4, horizontal portion 5 and vertical portion 6 and the latter terminates in a segment shaped head 7, provided concentrically of its curved edge or periphery with a pivotal notch 8.

9 is a horizontal plate support upon and secured to portion 5 of the step-shaped standard, and said support is provided with a depending marginal stiffening flange 10, and is provided at its opposite margin with

a series of notches 11. The plate support is also provided with a pair of facing supporting ears 12 stamped out of the body of the plate by preference, and pivoted to the flange 10 is a catch 14 for a purpose which 60 hereinafter appears.

A preferably sheet metal bracket consists of the body portion 15, provided at one end with a vertical and substantially right angle shaped arm 16, the vertical portion of said arm being disposed at the front side of the body portion 15, and provided with a downwardly facing shoulder 17, and the horizontal arm extending rearwardly in a plane below that of the body portion. At the opposite 70 end of the body portion is formed a substantially horizontal rearwardly projecting arm 18, and projecting upwardly from that end of the body portion from which arm 18 projects, is an arm 19, to which is secured 75 a handle 20. The body portion is provided with a curved guiding ear 21 and with a headed pivot 22, the former to receive the curved edge or periphery of the segmental head 7, hereinbefore mentioned, and the 80 notch to pivotally receive the pivot 22 with the head 7 thereof flanging over to coöperate with the guiding ear 21 in holding the bracket 15 and head 7 flatly together, as shown.

85 A slicing blade 21^a is fitted flatly against the rear side of the body portion 15 and has its cutting edge 22^a off-set to underlie said body portion 15, and to secure the slicing blade reliably in position, it is provided with 90 a plurality of obliquely-extending slots 23 and securing screws 24 extend into the said body portion 15 of the said pivoted bracket. The slots permit of a certain amount of adjustment of the blade and are preferably set 95 on a slant in order that the strain incident to the slicing operations shall be imposed on the undersides of the slots, to guard against accidental slippage or creepage of the blade.

25 is a gage paralleling the slicing blade 100 but set below and rearward of the same. This gage is provided at its outer end with a rearwardly projecting ear 26, to fit flatly against the horizontal portion of the arm 16, and is provided with a slot 27 to permit of 105 the bodily adjustment of the gage toward and from the vertical plane of the slicing blade. At its opposite or inner end the gage is provided with a rearwardly projecting ear 28, provided with a slot 29 to under- 110

lie and fit flatly against the arm 18, projecting from the body portion 15 of the pivoted slicer-blade-carrying bracket. A screw bolt 30 extends through the slot 27 and the rear end of arm 16 and is engaged by a clamping nut 31. A similar bolt 32 extends up through slot 29 and arm 18 and is engaged by a nut 33. By means of these bolts and nuts the gage can be adjusted toward and from the vertical plane of the slicing blade and the slots are of such length that when the gage is adjusted forward its full distance, the cutter will produce thin potato chips and when adjusted rearwardly its full distance, will produce "French fried" potatoes, provided it is equipped with a splitting attachment, hereinafter mentioned.

As a guide for the adjustment of the gage in the production of "shoestring" potatoes, the upper edges of the lower portion of arm 16 and ear 26 and the inner edges of arms 18 and 28, are provided with indicating notches 34, the notches on the arm 16 and ear 26, appearing in alignment in Fig. 4. In Fig. 1, the same notches 34 are shown out of alignment. Fig. 3 only, shows the notches 34 on the arm 18, and said figure also shows the ear 28 provided with a corresponding notch 34. When these notches all register, that is occupy the same vertical plane, the gage is adjusted, as above suggested, to produce "shoestring" potatoes.

36 is a pin projecting forwardly from the rear end of the gage and pivoted to the latter about midway its length and at its rear side is a turn button 37. 38 is a splitting plate adapted to fit flatly against the front side of the gage and provided with a hole 39 to receive the pin 36 of the gage. Plate 38 is also provided with an upturned lower edge 40 to receive the lower edge of the gage and with a rearwardly projecting flange 41 to fit upon the upper edge of the gage, said flange having an elongated opening 42 into which the turn button 37 can be turned to securely fasten the splitting plate to the gage. Ordinarily there will be at least two of these splitting plates, one provided with forwardly projecting splitting blades 43, spaced properly with respect to pivot 22, to slit slices of potato into "French fried" strips and the other with more closely arranged shorter splitting blades 44 for cutting thinner slices of potato into "shoestring" strips, the blades 44 being so positioned that they will pass through notches 11 in the pivotal operation of the body portion 15 provided the gage is adjusted forwardly its full distance.

When "French fried" potatoes are to be produced the gage, as hereinbefore stated, is adjusted rearwardly its full distance and necessitates or renders advisable the use of a support for that portion of the potato occupying a vertical plane between the blade

21 and the gage. To provide a support at this point, I provide a plate 45 at the underside of the plate support 9 and upheld by the supporting ears 12, and to guard against slippage of the plate 45 it is provided with an opening 45^a for the reception of an upturned end of the pivoted catch 14, as shown in Fig. 3. It is desirable that this plate 45 shall be as thin as possible and this being true, it is preferably formed with a depression 45^b to stiffen it. The plate is provided with rearwardly projecting fingers 46 into which the depressions 45^b extend, as shown in Fig. 1, and at their rear ends the fingers terminate in upstanding lugs 47 to arrest a vegetable at the proper point when the same is slid under the slicing blade when the latter is raised, preliminary to cutting a slice from the vegetable.

Assuming that it is desired to cut "French fried" potatoes, the parts will be arranged as shown in Figs. 1 to 3 inclusive. The operator will then grasp handle 20 and raise the pivoted bracket 15 and the parts carried thereby to a sufficient height to permit a potato to be placed upon plate support 9 and against the upstanding lugs 47 or the plate 38. The slicing blade is then brought down by pressure on the handle and by such action a slice is cut from the potato and at the same time this slice is subdivided into strips by the splitting blades 43. As the blade is lifted, the strips of potato fall from the fingers and the potato is shoved forward until either the lugs 47 or the plate 38 again limits such movement and then the slicing blade is brought down and a second slice is cut from the potato, and such slice is divided into strips by the blades 43, these operations being repeated until the requisite number of "French fried" strips have been produced.

In the event that it is desired to produce "shoestring" potatoes, the plate 38, provided with blades 43, is removed and is replaced by a plate 38 provided with blades 44. The gage is then attached forward the requisite distance, it being understood, of course, that the finger support 45 is first removed as the same is not adapted for use when "shoestring" potatoes are to be made. To make the "shoestring" potatoes, the manipulation of the slicing blade, above described, is repeated, it being obvious that in this case the slices produced are of substantially the same thickness as the distance between notches 11.

If it is desired to produce slaw it can be accomplished with the parts arranged for producing "shoestring" potatoes. If it is desired to produce potato chips, the gage plate is disposed as far forward as its slots 27 and 29 will permit and neither of the plates 38 will be employed.

From the above description it will be ap-

parent that I have produced a vegetable cutter embodying the features of advantage enumerated as desirable and which is susceptible of minor particulars without departing from the spirit and scope of the appended claims.

I claim:—

1. A vegetable cutter, comprising a supporting plate, a slicing blade to operate along the edge of said plate, a gage movable with the blade and extending parallel thereto, and a plate detachably mounted on the gage and provided with splitting blades projecting toward the vertical plane of the slicing blade.
2. A vegetable cutter, comprising a supporting plate, a slicing blade to operate along the edge of said plate, a gage movable with the blade and extending parallel thereto, a plate fitting flatly against the gage and provided with forwardly projecting splitting blades and also provided with rearwardly projecting flanges engaging the upper and lower edges of the gage, and means mounted on the gage for preventing accidental disengagement of the said plate therefrom.
3. A vegetable cutter, comprising a supporting plate having notches in its rear edge, a slicing blade to operate in a vertical plane adjacent to the notched edge of said plate, a gage parallel with and occupying planes below and rearward of the slicing blade, and splitting blades movable with and projecting forwardly from the gage and bearing such relation to notches of said supporting plate as to be capable of swinging therethrough as the slicing blade is operated.
4. In a vegetable cutter, a supporting plate, a swinging slicing blade to operate upon an article resting upon said plate, a gage movable with the blade and arranged parallel thereto and in planes rearward and below the latter, and a plate detachably secured to the supporting plate and underlying said slicing blade and provided with rearwardly projecting fingers spaced apart to permit the slicing blades to operate between them.
5. In a vegetable cutter, a supporting plate, a swinging slicing blade to operate upon an article resting upon said plate, a gage movable with the blade and arranged parallel thereto and in planes rearward of and below the latter, a plate secured flatly to the gage, provided with forwardly-projecting splitting blades, and a plate detachably secured to the supporting plate and underlying said slicing blade and provided with rearwardly projecting fingers spaced apart to permit the splitting blades to operate between them, and provided at their rear ends with upwardly projecting arms.
6. In a vegetable cutter, a supporting plate provided at its under side with sup-

porting ears, a pivoted catch carried by and below the plate, and a plate underlying the first-named plate and supported by said ears and provided with an opening engaged by said catch; said plate having fingers projecting rearwardly beyond the rear edge of the first-named plate and terminating at their rear extremities in upturned arms.

7. In a vegetable cutter, the combination of a supporting plate, a standard in fixed relation thereto, a frame pivoted to the standard, a substantially horizontal arm projecting rearwardly from said frame at its pivoted end, a right angle shaped arm at the opposite end of said frame, one part of the angle arm standing upright forward of the plane of the frame and the other part extending rearwardly, a gage arranged between said arms and adjustably secured at its opposite ends to the first-named arm and to the rear end of the right angle shaped arm, and a slicing blade secured to said frame and adapted to operate adjacent the rear edge of said supporting plate.

8. In a vegetable cutter, the combination of a supporting plate, a standard in fixed relation thereto, a frame pivoted to the standard, a substantially horizontal arm projecting rearwardly from said frame at its pivoted end, a right angle shaped arm at the opposite end of said frame, one part of the angle arm standing upright forward of the plane of the frame and provided with a downwardly disposed shoulder to limit downward movement of the frame by engaging the said supporting plate, and the other part extending rearwardly, a gage arranged between said arms and adjustably secured at its opposite ends to the first-named arm and to the rear end of the right angle shaped arm, and a slicing blade secured to said frame and adapted to operate adjacent the rear edge of said supporting plate.

9. In a vegetable cutter, a plate provided at one of its longitudinal margins with an upturned hook and at its other longitudinal margin with a flange provided with an opening, and also provided with a gage opening, and with a plurality of splitting blades extending at decided angles to its longitudinal edges, and arranged for cutting in parallel planes disposed at substantially equal distances apart.

10. In a vegetable cutter, a slicing blade carrying frame provided at one end with a horizontally arranged rearwardly projecting arm and at its other end with a vertically arranged rearwardly projecting arm, a gage plate paralleling said frame and provided at one end with a rearwardly projecting longitudinally slotted horizontal arm fitting against the first-named horizontal arm and at its other end with a rearwardly projecting vertically arranged and longitu-

dinally slotted arm fitting against the vertically disposed arm of said frame, clamping bolts extending through said slotted arms and said adjacent arms, and nuts engaging 5 said bolts to clamp adjacent arms reliably together.

11. In a vegetable cutter, a pivoted gage provided with a forwardly projecting pin near one end and a pivot button at its rear 10 side, and a plate fitting against the front side of said gage and provided with forwardly projecting splitting blades and with a hole to engage said pin, and with rearwardly projecting flanges to engage the 15 upper and lower edges of the gage, one of

the flanges having an opening adapted for engagement by said button.

12. In a vegetable cutter, the combination of a frame provided with rearwardly projecting pins, and a blade fitting flatly 20 against said frame and provided with obliquely extending slots engaging said pins, and with an off-setting portion underlying said frame.

In testimony whereof, I affix my signature, in the presence of two witnesses.

CHARLES W. OTT.
